Patented Oct. 14, 1913.

Fig. 1.

UNITED STATES PATENT OFFICE.

VICTOR LAUER, OF STILLWATER, OKLAHOMA.

CULTIVATOR.

1,075,832.

Specification of Letters Patent. Patented Oct. 14, 1913.

Application filed May 19, 1913. Serial No. 768,487.

To all whom it may concern:

Be it known that I, VICTOR LAUER, a citizen of the United States, and a resident of Stillwater, in the county of Payne and State 5 of Oklahoma, have made certain new and useful Improvements in Cultivators, of which the following is a specification.

My invention is an improvement in cultivators, and has for its object to provide a 10 wheeled device of the character specified, wherein the wheels are so connected to the cultivator, that the driver may simultaneously swing the wheels with respect to the cultivator to change the direction of movement of the cultivator, and may hold the 15 said wheels at any desired angle with respect to the cultivator.

In the drawing: Figure 1 is a rear view of the improved cultivator, Fig. 2 is a section on the line 2—2 of Fig. 1, and, Fig. 3 is a perspective view of a stirrup and its connections.

The present embodiment of the invention comprises a tubular body frame 1, having 25 connected therewith a tongue 2 and a seat 3, the tongue extending forwardly from the frame, and the seat being arranged at the rear thereof and above the level of the body frame. Brackets 4 are provided for connecting the seat with the body frame, the 30 said seat having a central depending rib 5 received between the rear ends of the brackets, the said brackets converging toward their rear ends as shown, and rivets 6 are 35 passed through the brackets and the rib to secure the seat in place. Each bracket is provided with a bearing 7 for engaging the body frame, and in front of the body frame the brackets converge to the tongue 2, and 40 are lapped upon the opposite sides thereof, and secured thereto by means of a bolt and nut 8. Wheels 9 are provided for supporting the frame, each wheel being journaled upon a spindle 10, and each spindle is received 45 at its inner end in a bearing sleeve 11. Each of the sleeves 11 is provided with an upward tubular extension 12, intermediate its ends, and the interior of each extension is separated from the bore of the sleeve 50 by a diaphragm 13. The spindles are secured in the bearing sleeves by means of set screws 14, the said set screws being passed through the sleeve and engaging the spindle, to prevent angular movement thereof with 55 respect to the sleeve.

An angle bar is arranged at each end of

the body frame, each of the said bars comprising integral arms 15 and 16 arranged at a right angle with respect to each other. The arm 15 of each angle bar or rod is received 60 in the adjacent end of the body frame, and the arm 16 of each of the said bars or rods is received in the extension 12 of the adjacent spindle bearing sleeve. A collar 17 is arranged on each arm 15 at the end of the 65 body frame, and each collar is held in adjusted position on the arm by means of a set screw 18. A similar collar 19 is arranged on each arm 16 at the top of the extension 12, each collar 19 being held in place by a 70 set screw 20, the said screw being threaded through the collar and engaging the arm. At each end the bearing frame is provided with a longitudinally extending hook 21, extending beyond the adjacent collar 17 and 75 having a lateral lug engaging outside the collar. The said hooks prevent disengagement of the arms 15 from the body frame, and each of the extensions 12 is provided with a similar hook 22 engaging outside of 80 the adjacent collar 19, to prevent disengagement of the arm 16 from the extension.

A ball 23 is arranged at the lower end of each of the arms 16, between the said end and the diaphragm 13, for supporting the 85 said arm, and for providing a bearing for the said arm upon which to rotate. Each of the extensions 12 is provided with an inwardly extending lug 24 near its upper end, and a cross head 25 is connected to the body 90 frame at the center thereof, by means of a hanger 26. The hanger passes through an opening 32 in the center of the cross head, and a nut 27 is threaded onto the hanger below the cross head, for pivotally connecting 95 the cross head to the hanger. The ends of the cross head are longitudinally slotted, as shown at 28 (Fig. 3) and a stirrup 29 is connected with each end of the cross head. Each of the said stirrups has a threaded 100 stem 30 extending through the adjacent slot, and a nut 31 engages the stem above the cross head. Each stirrup is provided with an integral laterally extending link 33, and each link is secured at its outer end to the 105 lug 24 of the adjacent extension.

Any suitable or desired form of cultivating mechanism may be supported by the body frame, the said mechanism forming no part of the present invention, and for that 110 reason not shown nor described.

In operation, the driver seated in the seat

3 engages the stirrups 29 with his feet. The slots 28 of the cross head permit a limited movement between the stirrups and the cross head. It will be obvious that when the cross head is swung at an angle to the shaft, or to the axes upon which the wheels rotate, there must be some movement between the stirrups and the cross head in order to permit such swinging movement. When the ends 5 of the cross head swing angularly as above-mentioned, the distance between the said ends and the adjacent stirrups is increased. By means of the stirrups and the cross head, the angle of the planes of the wheels with 10 respect to the direction of motion of the cultivator may be changed. It will be understood that when the hanger 29 at the right of Fig. 1, for instance, is pressed forwardly, the extension 12 will be oscillated on the 15 arm 16 of the angle bar, to vary the angle of the plane of the adjacent wheel to the direction of motion of the cultivator. When the stirrup is pushed forward as mentioned, the stirrup at the opposite end of the cross 20 head is moved rearwardly, the cross head swinging on the hanger. Thus the extension 12 at the opposite side of the cultivator is oscillated in the opposite direction to the first-named extension, so that the 25 wheels are swung simultaneously in the same direction to guide the cultivator through the field. The wheels may be held in the desired position, until the direction of motion has been changed, after which 30 they are swung into proper alignment with the cultivator. The weight of the cultivating mechanism and of the operator is supported on the balls 23, and the said balls provide a non-friction bearing for the said 35 weights.

I claim:-

1. A device of the character specified, comprising a tubular body frame, brackets each having a bearing intermediate its ends 45 engaging the body frame, said brackets converging in front and in rear of the body frame, a seat connected to the converging ends in rear of the frame, a tongue connected with the brackets in front of the 50 frame, an angle bar or rod at each end of the body frame, each of the said bars or rods consisting of two portions extending at a right angle to each other, one of the said portions of each bar or rod being received in the adjacent end of the body frame, a spindle bearing sleeve at each end of the body frame, each sleeve having an upward tubular extension for receiving the other arm of the adjacent 55 angle rod or bar, a collar secured adjustably to each arm of each angle bar or rod, hooks on the ends of the body frame and on the upper ends of the extension for engaging outside of the adjacent collar, each 60 of the said extensions having a lateral lug 65

near its upper end, a cross head at the center of the body frame, a pivotal connection between the cross head at the center thereof and the body frame, each end of the cross head being longitudinally slotted, a stirrup at each end of the cross head, each stirrup having a threaded stem extending through the adjacent slot and having a laterally extending link secured to the lug of the adjacent extension, a nut engaging the 70 stem above the cross head, a spindle in each bearing sleeve, means for preventing angular movement of the spindle with respect to the sleeve, and a wheel on each spindle. 75

2. A device of the character specified, 80 comprising a tubular body frame, a seat supported by the frame in rear thereof, a tongue connected with the frame at the front thereof, an angle bar or rod at each end of the body frame, each bar or rod consisting of two portions extending at a right angle to each other, one of the said portions of each bar or rod being received in the adjacent end of the body frame, a spindle bearing sleeve at each end of the body frame, 85 each sleeve having an upwardly extending tubular extension for receiving the other arm of the adjacent angle bar or rod, means in connection with the angle bars, the body frame and the extensions for preventing disengagement of the bars, a cross head at the center of the body frame, a hanger on the body frame to which the cross head is pivoted intermediate the ends of the cross head, a stirrup slidably connected with each end 90 of the cross head and having a limited longitudinal movement with respect thereto, each extension having a lateral inwardly extending lug, and each stirrup having a rigid outwardly extending link connected 95 with the lug of the adjacent extension. 100

3. A device of the character specified, comprising a tubular body frame, a seat supported by the frame in rear thereof, a tongue connected with the frame at the front 110 thereof, an angle bar or rod at each end of the body frame, each bar or rod consisting of two portions extending at a right angle to each other, one of the said portions of each bar or rod being received in the adjacent 115 end of the body frame, each sleeve having an upwardly extending tubular extension for receiving the other arm of the adjacent angle bar or rod, means in connection with the angle bars, the body frame and the extensions for preventing disengagement of the bars, a cross head at the center of the body frame, a hanger on the body frame to which the cross head is pivoted intermediate 120 the ends of the cross head, a stirrup slidably connected with each end of the cross head and having a limited longitudinal movement with respect thereto, and a rigid connection between each stirrup and the adjacent extension. 125

4. A device of the character specified, comprising a tubular body frame, a seat supported by the frame in rear thereof, a tongue connected with the frame at the front thereof, an angle bar or rod at each end of the body frame, each bar or rod consisting of two portions extending at a right angle to each other, one of the said portions of each bar or rod being received in the adjacent end of the body frame, a spindle bearing sleeve at each end of the body frame, each sleeve having an upwardly extending tubular extension for receiving the other arm of the adjacent angle bar or rod, means in connection with the angle bars, the body frame and the extensions for preventing disengagement of the bars, a cross head pivoted intermediate its ends to the body frame, and a stirrup rigid with each extension and having a sliding connection with the adjacent end of the cross head. 40
- 5 10 15 20 25 30 35
5. A device of the character specified, comprising a tubular body frame, a seat supported by the frame in rear thereof, a tongue connected with the frame at the front thereof, an angle bar or rod at each end of the body frame, each bar or rod consisting of two portions extending at a right angle to each other, one of the said portions of each bar or rod being received in the adjacent end of the body frame, a spindle bearing sleeve at each end of the body frame, each sleeve having an upwardly extending tubular extension for receiving the other arm of the adjacent angle bar. 45
- 50 55 60 65
- tubular extension for receiving the other arm of the adjacent angle bar or rod, means in connection with the angle bars, the body frame and the extensions for preventing disengagement of the bars, a cross head pivoted intermediate its ends to the body frame, and a stirrup rigid with each extension and having a sliding connection with the adjacent end of the cross head. 40
5. A device of the character specified, comprising a body frame, a seat supported by the frame in rear thereof, draft apparatus connected with the frame, an angle bar at each end of the body frame, each bar comprising a portion connected with the frame, and a depending portion, wheels for supporting the frame, spindles upon which the wheels are journaled, a sleeve for each spindle, each sleeve having an upwardly extending tubular extension for receiving the dependent portion of the adjacent angle bar, said portions being rotatable in the extensions, a cross head depending from the body frame at approximately the center thereof and mounted to swing with respect to the frame, a stirrup at each end of the cross head, each stirrup having a limited movement longitudinally of the cross head, and a rigid connection between each stirrup and the adjacent extension. 55
